Primary Examiner — Patricia Palasik*(74) Attorney, Agent, or Firm* — Pearne & Gordon LLP(57) **CLAIM**

The ornamental design for a welder enclosure, as shown and described.

DESCRIPTION

FIG. 1 is a front isometric view of a welder enclosure showing our new design, with a front tool compartment door in a closed position;

FIG. 2 is a front isometric view thereof, with the front tool compartment door in an open position;

FIG. 3 is a rear isometric view thereof, with a rear tool compartment door in a closed position;

FIG. 4 is a rear isometric view thereof, with the rear tool compartment door in an open position;

FIG. 5 is a front elevation view thereof;

FIG. 6 is a rear elevation view thereof;

FIG. 7 is a left side elevation view thereof;

FIG. 8 is a right side elevation view thereof;

FIG. 9 is a top view thereof; and,

FIG. 10 is a bottom view thereof.

The broken lines are for illustrative purposes only and form no part of the claimed design.
